(57) **CLAIM**

The ornamental design for a display panel or screen with graphical user interface, as shown and described.

DESCRIPTION

FIG. 1 is a front elevational view of a first embodiment of a display panel or screen with an image of a graphical user interface showing our new design.

FIG. 2 is a front elevational view of a second embodiment of a display panel or screen with an image of a graphical user interface showing our new design; and,

FIG. 3 is a front elevational view of a third embodiment of a display panel or screen with an image of a graphical user interface showing our new design.

The broken lines showing a camera illustrate environment, whereas the broken lines showing elements of the display panel or screen with graphical user interface illustrates portions of the article. No subject matter depicted in broken lines form part of the claimed design.

1 Claim, 3 Drawing Sheets
